(57) **CLAIM**

The ornamental design for a wheel, as shown and described.

DESCRIPTION

FIG. 1 is a top, front, left side perspective view of a wheel showing a first embodiment of the claimed design;

FIG. 2 is a top, rear, right side perspective view showing the first embodiment of the claimed design;

FIG. 3 is a front elevational view showing the first embodiment of the claimed design;

FIG. 4 is a rear elevational view showing the first embodiment of the claimed design;

FIG. 5 is a left side elevational view showing the first embodiment of the claimed design;

FIG. 6 is a right side elevational view showing the first embodiment of the claimed design;

FIG. 7 is a top plan view showing the first embodiment of the claimed design;

FIG. 8 is a bottom plan view showing the first embodiment of the claimed design;

FIG. 9 is a top, front, left side perspective view of a wheel showing a second embodiment of the claimed design;

FIG. 10 is a top, rear, right side perspective view showing the second embodiment of the claimed design;

FIG. 11 is a front elevational view showing the second embodiment of the claimed design;

FIG. 12 is a rear elevational view showing the second embodiment of the claimed design;

FIG. 13 is a left side elevational view showing the second embodiment of the claimed design;

FIG. 14 is a right side elevational view showing the second embodiment of the claimed design;

FIG. 15 is a top plan view showing the second embodiment of the claimed design;

FIG. 16 is a bottom plan view showing the second embodiment of the claimed design;

FIG. 17 is a top, front, left side perspective view of a wheel showing a third embodiment of the claimed design;

FIG. 18 is a top, rear, right side perspective view showing the third embodiment of the claimed design;

FIG. 19 is a front elevational view showing the third embodiment of the claimed design;

FIG. 20 is a rear elevational view showing the third embodiment of the claimed design;

FIG. 21 is a left side elevational view showing the third embodiment of the claimed design;

FIG. 22 is a right side elevational view showing the third embodiment of the claimed design;

FIG. 23 is a top plan view showing the third embodiment of the claimed design; and,

FIG. 24 is a bottom plan view showing the third embodiment of the claimed design.

The features thereof shown in dotted lines form no part in the claimed design.
